UNITED STATES PATENT OFFICE

2,373,252

TRUCK

Mark H. Martin, Reading, Pa., assignor to Birdsboro Steel Foundry and Machine Company, Birdsboro, Pa., a corporation of Pennsylvania

Application February 16, 1943, Serial No. 476,099

36 Claims. (Cl. 105—197.1)

My invention relates to railway car trucks of the freight car type and, in particular, a truck characterized by good riding qualities, capacity for high speed service, and maximum strength per pound of weight for satisfying all static and dynamic requirements.

The simple truss type of side frame which is now used in great numbers by the railroads and in which the bolster load is applied to a shallow beam section between the bolster guide columns has long been recognized as being less than completely efficient with respect to meeting the increased loadings of freight cars. As one solution of this problem, there has been proposed the so-called double truss side frame which is more particularly described and claimed in United States Letters Patent No. 1,652,808, dated December 13, 1927, to which reference may be made for structural details. Briefly, the patented structure incorporates a double truss system composed of a three panel, main truss in which the two vertical members are provided by the bolster guide columns and an auxiliary truss in the approximate form of a triangle. These trusses have a common compression member which constitutes the compression member of the side frame, while the tension portion of the main truss is defined by the usual horizontal beam member of the frame between the lower ends of the bolster columns and by the diagonal members extending towards the journal boxes, and the tension portion of the auxiliary truss extends upwardly and outwardly from near the center of the spring seat portion of the frame. As actually embodied in the frame, this auxiliary tension portion is offset or raised relative to the tension member of the main truss and forms triangular shaped reinforcements at the junctions of the bolster columns and spring seat portion. It has been ascertained that this construction materially strengthens the side frame by reducing or minimizing the deflection of the spring seat portion.

Many types of spring suspensions have been employed to transfer the bolster load to the foregoing type of frame, including simple coil spring groups and combinations of such springs and work absorptive springs or snubbers, but in all cases, so far as I am aware, the spring loading has been applied to the frame substantially inwardly of the bolster guide columns and against the spring seat portion of the frame. Accordingly, the load is concentrated generally at the center of the frame with the result that the full

strength potentialities of the frame design in relation to weight are not secured.

It is therefore one object of my invention to provide a truck equipped with double truss side frames of the type indicated above and spring groupings which are arranged to insure a better distribution of the bolster load to the side frames than is obtained in previous designs with a resulting economy of metal in the frame and low average maximum fibre stresses.

A further object is to devise a truck of the character indicated in which the spring load is divided between the main and auxiliary trusses of the side frame in any desired ratio.

A further object is to provide a truck wherein a portion of the bolster load is distributed directly to the auxiliary truss tension member of the side frame through a leaf spring so that this member acts as a spring load carrying element in addition to transmitting that portion of the bolster load which is distributed to the central portion of the side frame through the coil springs.

A further object is the provision of a double truss side frame assembly which incorporates a non-synchronous spring suspension, certain portions of the suspension transmitting the bolster load directly to the spring seat portion of the frame constituting a part of the main truss and other portions transmitting directly to the auxiliary truss.

These and further objects of my invention will be set forth in the following specification, reference being had to the accompanying drawings, and the novel means by which said objects are effectuated will be definitely pointed out in the claims.

In the drawings:

Fig. 1 is a side elevation of one form of my improved truck, partly in section.

Fig. 2 is a sectional plan view of one of the side frames taken along the line 2—2 in Fig. 1.

Fig. 3 is a section along the line 3—3 in Fig. 1 showing the spring seat for an end of the leaf spring.

Fig. 4 is a perspective view of a spring seat block which may be applied to double truss side frames now in use to form the frame shown in Fig. 1.

Fig. 5 is a fragmentary, sectional side elevation of a modified form of double truss side frame which incorporates my invention.

Fig. 6 is a section along the line 6—6 in Fig. 5. Referring to Figs. 1 to 3, inclusive, there is illustrated by way of example one form of my invention as applied to a spring plankless truck in

which the side frames embody so-called radial column guides to provide a controlled relative movement between the bolster and side frames and accordingly a controlled flexibility of the truck. My improved truck is equipped with the usual wheels 10 and journals 11 which are received within journal boxes 12 having the conventional wedges and brasses (not shown). The boxes are located at the ends of and preferably formed integrally with a generally hollow side frame 13 comprising a compression member 14, a tension member 15 and bolster guide columns or strut portions 16 which space intermediate portions of the compression and tension members and define between the columns a bolster window opening 17. As illustrated, the members are joined to each other and to the journal boxes 12, although the latter may be separately formed if desired and in this event, the ends of the frame would be jaw-shaped in the well known manner.

Between the columns 16, the tension member 15 is formed generally with a box section comprising an upper web 18, a lower web 19 and side walls 20. As indicated in Fig. 2, the web 18 is extended laterally beyond the walls 20 to form shelves 21 which together with the web 18 form a spring seat portion or support as hereinafter explained and these shelves may be braced by gusset portions 22 which extend laterally from the walls 20 and underlie the shelves.

In order to rigidify and strengthen the tension member 15 and the junction between this member and the columns 16, the upper portion of the member is offset or embossed along the longitudinal center line of the frame on each side of the junction of the respective bolster columns with the member. This offsetting of the tension member takes the form of upper, diagonally disposed webs 23 which begin near and on opposite sides of the center of the web 18 and extend diagonally upward through the bolster guide columns 16 towards the ends of the frame. The width of the web 23 is somewhat less than the transverse thickness of the tension member 15 and the beam section of this member between the columns and is connected to the diagonal tension portions of the member and the web 18 by depending side walls 24. Inwardly of the columns 16, the webs 23 and side walls 24 form triangular reinforcements or embossments 25 which are connected to the columns and web 18.

In effect, the webs 23 and side walls 24 provide an auxiliary tension reinforcing portion for the main tension member 15 and also provide in conjunction with the common compression member an auxiliary truss which cooperates with the main truss of the side frame comprising the members 14 and 15 and the columns 16. Generally speaking, this construction stiffens the frame, reduces the deflection of the portion of the main tension member between the columns 16 and permits an increase in the strength of the frame for any given weight. For further details regarding the structural aspects of the frame and the truss design theory involved, attention is directed to the above noted patent.

In the particular side frame illustrated in Fig. 1, the columns 16 are provided with guiding surfaces 26 which possess a concave, cylindrical curvature, the axis of the curvature coinciding with the vertical center line 27 of the side frame. The surfaces 26 have guiding relation with complementary convex surfaces 28 provided on each

end of a truck bolster 29 which may possess a box section and which is vertically slidable between the columns. This construction provides for a certain flexibility of the truck due to the capacity for relative movement between the bolster and side frames occasioned when one frame tends to lead the other. Full bearing contact between the bolster and frames is maintained during this movement in contrast to the limited and sometimes critical line contact between a straight side bolster and correspondingly shaped bolster columns under similar conditions which results in excessive wear and the loss of the preferred clearances between the bolster and columns. Endwise and angular movements of the bolster are limited by inner and outer, radial, guide lugs 30 and 31, respectively (see Fig. 2), the latter being shortened in length, as shown in Fig. 1, to enable the bolster to clear the triangular reinforcements 25 when dropped for separation from the side frames.

The bolster is partially supported by a cluster of coil springs 32 arranged as an inner and an outer group relative to the side frame, four such springs being shown in the present instance, although the number may be varied as desired. The upper ends of the springs bear against an upper spring plate 33 which seats against the under side of the bolster and is held in position by lugs 34 projecting into apertures 35 in the bottom wall of the bolster, while the lower ends rest on a bottom spring plate 36 which bears on the web 18 and shelves 21. The periphery of the plate 36 may be upwardly flanged as at 37 to retain the lower ends of the springs 32 and notched as at 38 so that the ends of the plate lengthwise of the frame straddle the reinforcements 25.

The bolster is also supported on a semi-elliptic leaf spring 38 which is disposed lengthwise of the frame between the groups of coil springs 32 and the center band 40 of the leaf spring projects through an opening 41 in the plate 33 for direct loading by the bolster. A centering lug 42 may extend from the band 40 into an aperture 43 provided in the lower web of the bolster. The ends of the leaf spring are seated in pockets 44, each of which is included in a block 45 integrally formed with and extending upwardly from a reinforcement 25 adjacent a bolster column 16 and provided with side flanges 46 as retainers for the ends of the spring.

Under operating conditions, the springs 32 and 38 act in unison and in parallel, load transfer relation to transmit loads to the side frame. Owing to the work absorptive nature of the spring 38, its natural period of vibration is different from the coil springs 32 so a mutual dampening action is set up which inhibits any tendency towards synchronous vibration. This type of vibration, common in the simple coil spring suspension, may, in the event of synchronization with the frequency of shocks transmitted to the truck by wheel or rail irregularities or out of surface rail joints, increase the amplitude of the roll of the car body sufficiently to cause derailment on curves or may drive the springs solid with resulting uncushioned shocks on the rails and possible failure of the springs.

This spring grouping distributes the load well over the portion of the tension member between the bolster columns and allocates the load to the main and auxiliary trusses of the frame. In this connection, it will be noted that the auxiliary truss portion represented by the web 23 acts as a spring load carrying part in addition to its usual

load transmitting function with respect to that portion of the bolster load which is applied to the web 18. By delivering the leaf spring load to the blocks 45 which are adjacent and connected to the columns 16, it is possible to avoid concentrating the bolster load at the center of the frame with the accompanying objectionable tendency towards deflection of the portion of the tension member between the bolster columns. It is therefore possible to avoid areas of critical loading on the frame and to accordingly distribute the metal in the frame in a more effective manner for any given strength factor. In general, all of the foregoing features have been combined so that the truck is characterized by good riding qualities, capacity for high speed service and easy assembly and replacement of the several parts of the truck.

It is contemplated that existing double truss side frames may be conditioned to provide the frame shown in Fig. 1 by means of blocks 47 (see Fig. 4) whose under side is shaped to fit and which would be welded or otherwise secured to a reinforcement 25 adjacent a column 16. This block would be comparable to the block 45 in Fig. 1 and would include a spring pocket 48 flanked by retaining flanges 49.

In Figs. 5 and 6 is illustrated a modified design which differs only in that the ends of a semi-elliptic, leaf spring 50, comparable to the spring 39, extends through openings 51 in bolster columns 52, respectively, for support on auxiliary tension webs 53, corresponding to the webs 23, outwardly of the columns. Otherwise, this modification is identical with that shown in Fig. 1.

It will be understood that the invention is not restricted to a spring plankless, radial column truck, but may also be incorporated in the more common types of truck which utilize, spring planks or flat sided bolsters and bolster columns.

I claim:

1. In a truck, the combination of a truss side frame having a spring seat and bolster guide columns at the ends of the seat, an auxiliary truss reinforcement for the tension member of the frame extending in opposite directions upwardly from and having spring pockets adjacent the ends of the spring seat, a bolster slidable between the columns, and a spring assembly comprising coil springs between the bolster and spring seat and a semi-elliptic leaf spring loaded by the bolster and disposed lengthwise of the frame, the ends of the leaf spring seating in the pockets.

2. In a truck, the combination of a truss side frame having a compression member, a tension member, bolster guide columns extending between the members, a spring seat included between the columns and an auxiliary truss reinforcement for the tension member extending in opposite directions upwardly from the spring seat, a bolster slidable between the columns, and a spring assembly comprising freely acting and work absorptive springs loaded by the bolster, one kind of springs resting on the spring seat and the other on the reinforcement.

3. In a truck, the combination of a truss side frame having a compression member, a tension member, bolster guide columns extending between the members, a spring seat included between the columns and an auxiliary truss reinforcement for the tension member beginning inwardly of the columns and extending in opposite directions upwardly from the spring seat, a bolster slidable between the columns, and a spring assembly comprising coil springs and a semi-elliptic leaf

spring loaded by the bolster, the coil springs resting on the spring seat and the ends of the leaf spring on the reinforcement.

4. In a truck, the combination of a truss side frame having a compression member, a tension member, bolster guide columns extending between the members, a spring seat included between the columns and an auxiliary truss reinforcement for the tension member beginning inwardly of the columns and extending upwardly in opposite directions from the spring seat, a bolster slidable between the columns, and a spring assembly comprising coil springs and a semi-elliptic leaf spring loaded by the bolster, the coil springs resting on the spring seat and the ends of the leaf spring extending through openings in the columns for support by the reinforcement.

5. In a truck, the combination of a truss side frame having a spring seat, bolster guide columns at the ends of the seat, and a tension member provided with main and auxiliary truss tension portions, a bolster slidable between the columns, and a spring assembly comprising coil springs between the bolster and spring seat and leaf spring means loaded by the bolster and supported on the auxiliary tension portion.

6. In a truck, the combination of a truss side frame having a compression member, a tension member provided with main and auxiliary truss tension portions, bolster guide columns extending between the members and a spring seat included between the columns, a bolster slidable between the columns, and a spring assembly comprising coil springs between the bolster and spring seat and leaf spring means supported on the auxiliary tension portion inwardly of and close to the columns.

7. A side frame comprising a compression member, a tension member having main and auxiliary truss tension portions, bolster guide columns extending between the members and a spring seat included between the columns, the auxiliary tension portions beginning inwardly of the columns and extending upwardly in opposite directions from the spring seat, and a leaf spring seat on the auxiliary portion adjacent each column.

8. A side frame comprising a compression member, a tension member having main and auxiliary truss tension portions, bolster guide columns extending between the members and a spring seat included between the columns, the auxiliary tension portions beginning inwardly of the columns and extending upwardly in opposite directions from the spring seat and each column being apertured to a size adequate to receive a leaf spring for support by the auxiliary portions outwardly of the columns.

9. In a truck, the combination of a side frame comprising a compression member, a tension member having main and auxiliary truss tension portions, bolster guide columns extending between the members to form a window opening, the auxiliary tension portions beginning inwardly of the columns and extending upwardly in opposite directions, and a semi-elliptic leaf spring disposed in the opening for loading by a bolster and having its ends supported on the auxiliary portion adjacent the columns.

10. In a truck, the combination of a side frame comprising a compression member, a tension member having main and auxiliary truss tension portions, bolster guide columns extending between the members to form a window opening, the auxiliary tension portions beginning inwardly of the columns and extending upwardly in opposite

directions, and a semi-elliptic leaf spring disposed in the opening for loading by a bolster and having its ends extending through openings in the columns for support by the auxiliary portions outwardly of the columns.

11. In truck construction employing a double truss side frame having a main tension member and an auxiliary truss tension reinforcing portion therefor, the member having a spring seat for supporting bolster loaded springs, a block shaped for securing to and bearing on the portion and having a pocket for receiving one end of another bolster loaded spring.

12. In a truck, the combination of a double truss side frame having a spring seat and embossments extending oppositely from the seat along the frame tension member to form an auxiliary truss reinforcement, a bolster operably related to the frame, and a spring assembly comprising coil springs between the bolster and spring seat and a leaf spring loaded by the bolster and having its ends bearing on the embossments.

13. In a truck, the combination of a double truss side frame having a compression member, a tension member, bolster guide columns extending between the members, a spring seat on the tension member between the columns, embossments extending from the seat inwardly of the columns in opposite directions along the tension member to form an auxiliary truss reinforcement for the frame, a bolster slidable between the columns, and a spring assembly comprising coil springs between the bolster and spring seat and a leaf spring loaded by the bolster and having its ends bearing on the embossments inwardly of the columns.

14. In a truck, the combination of a double truss side frame having a compression member, a tension member, bolster guide columns extending between the members, a spring seat on the tension member between the columns, embossments extending oppositely from the seat along the tension member, a bolster slidable between the columns, and a spring assembly comprising coil springs between the bolster and spring seat and a leaf spring loaded by the bolster and having its ends extending through openings in the columns for support by the embossments.

15. In a truck, the combination of a truss side frame having a spring seat and embossments extending oppositely from the seat along the frame tension member to form an auxiliary truss reinforcement for the frame, the embossments having spring pockets adjacent the ends of the spring seat, a bolster operably related to the frame, and a spring assembly comprising coil springs between the bolster and spring seat and a semi-elliptic leaf spring loaded by the bolster and disposed lengthwise of the frame, the ends of the leaf spring seating in the pockets.

16. In a truck, the combination of a truss side frame having a compression member, a tension member, bolster guide columns extending between the members, a spring seat included between the columns, embossments for the tension member beginning inwardly of the columns and extending in opposite directions from the spring seat, a bolster slidable between the columns, and a spring assembly comprising coil springs and a semi-elliptic leaf spring loaded by the bolster, the coil springs resting on the spring seat and the ends of the leaf spring extending through openings in the columns for support by the embossments.

17. In a truck, the combination of a truss side frame having a compression member, a tension

member provided with a main tension portion and embossments extending oppositely from the central part of and along the main tension portion to form an auxiliary truss reinforcement for the frame, bolster guide columns extending between the members and a spring seat included between the columns, a bolster slidable between the columns, and a spring assembly comprising coil springs between the bolster and spring seat and a leaf spring means supported on the embossments inwardly of and close to the columns.

18. A side frame comprising a compression member, a tension member provided with a main tension portion and embossments therefor, bolster guide columns extending between the members and a spring seat included between the columns, the embossments beginning inwardly of the columns and extending upwardly in opposite directions from the spring seat to form an auxiliary truss reinforcement for the frame, and a spring seat on each embossment adjacent each column.

19. A side frame comprising a compression member, a tension member provided with a main tension portion and embossments therefor, bolster guide columns extending between the members and a spring seat included between the columns, the embossments beginning inwardly of the columns and extending upwardly in opposite directions from the spring seat to provide an auxiliary truss reinforcement for the main tension portion and each column being apertured to a size adequate to receive a leaf spring for support by the associated embossment outwardly of the column.

20. In a truck, the combination of a side frame comprising a compression member, a tension member having a main tension portion and embossments therefor, bolster guide columns extending between the members to form a window opening, the embossments beginning inwardly of the columns and extending upwardly in opposite directions to provide an auxiliary truss reinforcement for the main tension portion, and a semi-elliptic leaf spring disposed in the opening for loading by a bolster and having its ends extending through openings in the columns for support by the embossments outwardly of the columns.

21. In truck construction employing a double truss side frame having a main tension member and embossments extending oppositely from the central part of and along the member to form an auxiliary truss reinforcement therefor, the member having a spring seat for supporting bolster loaded springs, a block shaped for securing to and bearing on each embossment and having a pocket for receiving one end of another bolster loaded spring.

22. In a truck, the combination of a side frame having a compression member, a tension member, bolster guide columns bridged between the members, a spring seat on the tension member between the columns and auxiliary, diagonal tension portions extending from the spring seat inwardly of the columns in opposite directions toward the ends of the tension member, a bolster slidable between the columns, and a spring assembly comprising coil springs between the bolster and spring seat and plate spring means loaded by the bolster and supported on the portions.

23. In a truck, the combination of a side frame having a compression member, a tension member, bolster guide columns bridged between the members, a spring seat on the tension member between the columns and auxiliary, diagonal tension members extending from the spring seat inwardly of the columns in opposite directions toward the

ends of the tension member, a bolster slideable between the columns, and a spring assembly comprising coil springs between the bolster and spring seat and plate spring means loaded by the bolster and supported on the auxiliary members, the coil springs and plate spring means being arranged in parallel, load transfer relation.

24. In a truck, the combination of a side frame having a compression member, a tension member, bolster guide columns bridged between the members, a spring seat on the tension member between the columns and auxiliary, tension portions extending from the spring seat inwardly of the columns in opposite directions toward the ends of the tension member, a bolster slideable between the columns, and a spring assembly comprising coil springs between the bolster and spring seat and a leaf spring intermediately loaded by the bolster and having its ends bearing on the portions.

25. In a truck, the combination of a side frame having a compression member, a tension member, bolster guide columns bridged between the members, a spring seat on the tension member between the columns and auxiliary, diagonal tension portions extending from the spring seat inwardly of the columns in opposite directions toward the ends of the tension member, a bolster slideable between the columns, and a spring assembly comprising coil springs between the bolster and spring seat and a leaf spring disposed lengthwise of the frame and intermediately loaded by the bolster, the ends of the leaf spring bearing on the portions.

26. In a truck, the combination of a side frame having a compression member, a tension member, bolster guide columns bridged between the members to include a window opening, a spring seat on the tension member between the columns and auxiliary, diagonal tension portions extending from the spring seat inwardly of the columns in opposite directions toward the ends of the tension member, a bolster slideable between the columns, and a spring assembly comprising coil springs between the bolster and spring seat and plate spring means having a part loaded by the bolster within the window opening and supported on the portions.

27. In a truck, the combination of a side frame having a compression member, a tension member, bolster guide columns bridged between the members to include a window opening, a spring seat on the tension member between the columns and auxiliary, diagonal tension portions extending from the spring seat inwardly of the columns in opposite directions toward the ends of the tension member, a bolster slideable between the columns, and a spring assembly comprising coil springs between the bolster and spring seat and a leaf spring intermediately loaded by the bolster within the window opening and having its ends bearing on the portions.

28. In a truck, the combination of a side frame having a compression member, a tension member, bolster guide columns bridged between the members to include a window opening, a spring seat on the tension member between the columns and auxiliary, diagonal tension portions extending from the spring seat inwardly of the columns in opposite directions toward the ends of the tension member, a bolster slideable between the columns, and a spring assembly comprising coil springs between the bolster and spring seat and a leaf spring disposed lengthwise of the frame and intermediately loaded by the bolster within

the window opening, the ends of the leaf spring bearing on the portions.

29. In a truck, the combination of a side frame having a compression member, a tension member, bolster guide columns bridged between the members, a spring seat on the tension member between the columns and auxiliary, diagonal tension portions extending from the spring seat inwardly of the columns in opposite directions toward the ends of the tension member, a bolster slideable between the columns, and a spring assembly comprising a central cluster of coil springs between the bolster and spring seat and leaf spring means loaded by the bolster and having its ends extending in opposite directions from the cluster for support on the portions.

30. In a truck, the combination of a side frame having a compression member, a tension member, bolster guide columns bridged between the members, a spring seat on the tension member between the columns and auxiliary, diagonal tension portions extending from the spring seat inwardly of the columns in opposite directions toward the ends of the tension member, a bolster slideable between the columns, and a spring assembly comprising a central cluster of coil springs between the bolster and spring seat and leaf spring means loaded by the bolster and extending lengthwise of the frame and having its ends projecting in opposite directions from the cluster for support on the portions.

31. In a truck, the combination of a side frame having a compression member, a tension member, bolster guide columns bridged between the members, a spring seat on the tension member between the columns and auxiliary, diagonal tension portions extending from the spring seat inwardly of the columns in opposite directions toward the ends of the tension member, a bolster slideable between the columns, and a spring assembly comprising a central cluster of coil springs arranged in inner and outer groups between the bolster and spring seat and leaf spring means loaded by the bolster and extending lengthwise of the frame between the groups and having its ends projecting in opposite directions from the cluster for support on the portions.

32. In a truck, the combination of a side frame having a compression member, a tension member, bolster guide columns bridged between the members, a spring seat on the tension member between the columns and auxiliary, diagonal tension portions extending from the spring seat inwardly of the columns in opposite directions toward the ends of the tension member, a bolster slideable between the columns, and a spring assembly comprising coil springs between the bolster and spring seat and plate spring means loaded by the bolster and supported on the portions adjacent the columns.

33. In a truck, the combination of a side frame having a compression member, a tension member, bolster guide columns bridged between the members, the members and columns constituting a main truss, a spring seat on the tension member between the columns and auxiliary truss portions extending from the spring seat inwardly of the columns in opposite directions toward the ends of the tension member, a bolster slideable between the columns, and a spring assembly comprising coil springs between the bolster and spring seat and plate spring means loaded by the bolster and supported by the portions at an elevation higher than the spring seat.

34. In a truck, the combination of a side frame

having a compression member, a tension member, bolster guide columns bridged between the members to include a window opening, the members and columns constituting a main truss, a spring seat on the tension member between the columns and auxiliary truss portions extending from the spring seat inwardly of the columns in opposite directions toward the ends of the tension member, a bolster slidable between the columns, and a spring assembly comprising coil springs between the bolster and spring seat and plate spring means having a part loaded by the bolster within the window opening and supported on the portions at an elevation higher than the spring seat.

35. In a truck, the combination of a side frame having a compression member, a tension member, bolster guide columns bridged between the members to include a window opening, the members and columns constituting a main truss, a spring seat on the tension member between the columns and auxiliary truss portions extending from the spring seat inwardly of the columns in opposite

5 directions toward the ends of the tension member, a bolster slidable between the columns, and a spring assembly comprising coil springs between the bolster and spring seat and a leaf spring intermediately loaded by the bolster within the window opening and having its ends bearing on the portions at an elevation higher than the spring seat.

10 36. In a truck, the combination of a truss side frame having a compression member, a tension member, bolster guide columns extending between the members, a spring seat included between the columns and an auxiliary truss reinforcement for the tension member extending in opposite directions upwardly from the spring seat, a bolster slidable between the columns, and a non-synchronous spring assembly comprising springs having different periods of vibration loaded by the bolster, springs having the same period resting on the spring seat and the other 15 springs on the reinforcement.

20 MARK H. MARTIN.
